UNITED STATES PATENT OFFICE.

DAVID S. HIGHKIN, OF BALTIMORE, MARYLAND.

DENTAL BRIDGEWORK.

1,345,595.

Patented July 6, 1920.

Application filed May 7, 1920. Serial No. 379,569.

To all whom it may concern:

Be it known that I, DAVID S. HIGHKIN, a citizen of the United States, residing at Baltimore, in the State of Maryland, have 5 invented certain new and useful Improvements in Dental Bridgework, of which the following is a specification.

The present invention relates to dental bridgework, and more particularly for anterior teeth, the object being to provide simple and effective means whereby the facings can be securely mounted on the backing, reinforced and braced against accidental breakage, and yet will permit the ready 10 removal of any individual tooth facing from the backing and its replacement by a new facing without altering or changing the backing.

The preferred form of construction is 15 illustrated in the accompanying drawings, wherein:—

Figure 1 is a front elevation of the facing, Fig. 2 is an edge view thereof,

Fig. 3 is a vertical sectional view,

Fig. 4 is a rear elevation,

Fig. 5 is a front elevation of the backing,

Fig. 6 is an edge view of the same, with the solder in place,

Fig. 7 is a vertical sectional view through Fig. 6,

Fig. 8 is a vertical sectional view through the backing without the solder,

Fig. 9 is a rear elevation of the assembled facing and backing,

Fig. 10 is a vertical sectional view through a completed bridge, and

Fig. 11 is a rear elevation of a portion of a bridge with parts broken away,

Fig. 12 is a vertical sectional view through 40 a modified facing during the process of construction,

Fig. 13 is a similar view of the completed tooth illustrated in Fig. 12.

In the embodiment illustrated in Figs. 45 1-11 inclusive, the facing is designated 14 and is preferably porcelain, with front and rear faces, the main portions of which are substantially parallel, and tapered inner and outer ends 15 and 16. Embedded in the 50 central portion of the facing, and extending to the rear face thereof, is a socket piece 16^a that is internally threaded, as illustrated at 17. Alongside this socket piece a socket 18 is formed in the facing.

55 The backing is designated 19 and is preferably a relatively thin sheet of metal, as

gold, having offset end margins 20 and 21 that conform to the correspondingly shaped end portions of the rear face of the facing 14. The backing is provided with a centrally disposed rearwardly extending enlargement or boss 22 provided with an opening 23 therethrough that alines with the socket 16^a and has its rear end countersunk as shown at 24. The backing furthermore 60 is provided with a positioning stud 25 carried by the boss and adapted to engage in the socket 18 when the backing is in place, as shown more particularly in Fig. 10.

It will be evident particularly by reference to Fig. 10 that the backing conforms to and fits throughout its extent against the rear face of the facing 14 and is held in place by a headed screw 26 that passes through the opening 23 and is screwed into 70 the socket piece 16^a, the head of said screw entering the countersunk portion 24 of said opening 23. The two elements or members are thus effectively held together. In using the teeth for bridge-work, a series of them 80 are placed edge to edge and the backings are connected by the usual solder 27 that extends over the various backings, bridging the joints between them and being flush with the rear end or face of each boss, thus 85 leaving the heads of the screws 26 exposed and available, as shown in Fig. 11.

This structure has various advantages. In the first place, it will be clear that each facing is effectively supported and yet practically no metal is exposed to view, thereby producing a most natural appearance. Any facing however, may be detached from the bridge by removing the screw 26 which holds it in place, so that if one is defaced 95 or injured, it may be substituted by another without difficulty and without the necessity of working over or altering the bridge. Moreover a bridge constructed as above described utilizes but very little metal, and 100 can be easily and expeditiously manufactured, thereby saving expense in both time and material.

As is well known to those skilled in the art, platinum is the best metal available for 105 embedment in porcelain facings, and the socket pieces 16^a therefore are preferably made of this material. Platinum, however, is very expensive and if desired the threads to engage with the screw may be formed 110 integral with the facing element itself. Thus, as illustrated in Figs. 12 and 13, the

facing element is designated 14^a and is baked, with a threaded plug of platinum 16^b embedded therein. After the facing is completed this plug of platinum may be removed in any suitable manner. For example, it can be dissolved by chemicals, such as aqua regia, the platinum being afterward recovered by precipitation in a well known manner. This therefore leaves the socket 10 with the threads 17^a formed of and directly in the porcelain facing, as shown in Fig. 13. Therefore when a screw is threaded thereinto and cemented, it will effectively hold the facing to the backing.

15 From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

20 25 Having thus fully described my invention, what I claim as new, and desire to secure by Letters Patent, is:—

1. In dental bridgework, a facing provided with a threaded socket in its rear side 30 and a second socket alongside the same, a backing having an opening that alines with the threaded socket, and a projection that enters the second socket, and a screw that passes through said opening in the backing 35 and engages in the threaded socket to hold the backing and facing together.

2. In dental bridgework, a facing provided with spaced sockets in its rear side, a backing that fits against the rear side of the 40 facing and is provided with a rearwardly

extending boss and a forwardly extending positioning stud that enters one of the sockets, and a device for holding the facing to the backing, engaging said backing and entering the other socket.

3. In dental bridgework, a facing provided with a threaded socket in its rear side and a second socket alongside the same, a backing having a rearwardly extending boss provided with an opening that alines with the threaded socket and a projection that enters the second socket, and a screw that passes through said opening in the backing and engages in the threaded socket to hold the backing and facing together.

4. In dental bridgework, a plurality of facings provided with threaded sockets in their rear sides and sockets alongside the same, individual backings for the facings having rearwardly extending bosses provided with openings that aline with the threaded sockets and positioning studs that enter the other sockets, screws passing through the openings and seated in the threaded sockets, and a binding body connecting the various backings and covering the same, leaving the screws exposed.

5. In dental bridgework, a facing provided with a metal socket piece having an internally threaded bore that opens through the rear side of said facing, said facing having a rearwardly opening socket alongside the socket piece, a backing having an opening that alines with the bore of the socket piece and a stud that enters the socket, and a screw that passes through the opening and is threaded into the socket piece.

In testimony whereof I affix my signature.

DAVID S. HIGHKIN.
